UNITED STATES PATENT OFFICE

2,479,615

AMALGAMATOR, INCLUDING ELECTRICAL
PRECIPITATION MEANS

Richard L. Guizzetti, Golden, Colo.

Application April 16, 1948, Serial No. 21,447

4 Claims. (Cl. 209—179)

1

This invention relates to methods and apparatus for recovering precious metals from ore bodies, and more particularly to a system of recovering fine gold from gold bearing sands by electrical precipitation.

A main object of the invention is to provide a novel and improved process for removing gold from gold bearing sand which is efficient in operation, which requires a minimum amount of human supervision, and which is especially useful in situations where the gold particles are of such fineness that they would not be recoverable by placer methods of ore separation.

A further object of the invention is to provide an improved apparatus for separating gold from gold bearing sands by electrical precipitation, said apparatus being relatively simple in construction, easy to operate and providing a high degree of recovery of gold from the gold bearing sand, particularly where the ore material is highly comminuted so that ordinary gold separation apparatus cannot be effectively employed.

Further objects and advantages of the invention will become apparent from the following description and claims, and from the accompanying drawings, wherein:

Figure 1 is a vertical cross-sectional view taken through a gold separating apparatus constructed in accordance with the present invention.

Figure 2 is a detail plan view of one of the electrode plates employed in the apparatus of Figure 1.

Figure 3 is an enlarged cross-sectional detail view taken on line 3—3 of Figure 2.

Figure 4 is an enlarged cross-sectional detail view taken on line 4—4 of Figure 2.

Figure 5 is an enlarged cross-sectional detail view taken on line 5—5 of Figure 2.

Figure 6 is an enlarged cross-sectional detail view taken on line 6—6 of Figure 2.

Figure 7 is an enlarged fragmentary cross-sectional view similar to Figure 3 but illustrating a modification of the present invention wherein multiple electrode plates are employed and wherein electrically charged mercury is carried on both sides of the electrode plates.

Figure 8 is a schematic view illustrating the modification of the invention wherein multiple electrode plates are employed.

Referring to the drawings, 11 designates a housing having a top wall 12 in which is supported a generally funnel-shaped hopper 13. The outlet spout of the hopper is designated at 14 and is provided with a heater coil 15 wound on an insulating heat-resistant sleeve 16 encircling and secured to outlet spout 14.

Mounted on top wall 12 are supports 17 and 18 on which are journalled respective rollers 19 and 20 carrying an end portion of a conveyor belt 21

2

which is adapted to feed ore into hopper 13 from a suitable source.

Designated at 22 is a hollow rectangular pedestal and projecting vertically from opposite walls thereof are respective post members 23 and 24, preferably of insulating material. Threaded through the upper portions of post members 23 and 24 are respective horizontal sleeve members 25 and 26 provided with hand wheels 27 and 28 for adjusting the sleeve members. Said sleeve members are internally threaded and engaged therein are respective horizontal shaft members 29 and 30. Secured to shaft member 29 is a first electrode plate 31 and secured to shaft member 15 30 facing said first electrode plate is a second electrode plate 31' similar in construction to the first plate.

Referring now to Figures 2 to 6, each electrode plate comprises a rectangular body of insulating material formed with a plurality of inclined, generally circular grooves 32, the ends of adjacent grooves being connected by semi-circular elbow conduits 33 embedded in the plate body. Communicating with the top groove is an inlet conduit 25 34 embedded in said body and communicating with the end of the bottom groove is an outlet conduit 35 similarly embedded. Secured to the face of the plate are a plurality of spaced vertical scraper bars 36 of insulating material which traverse the respective inclined grooves 32 and which have blade-like projections 36' extending transversely across the upper portions of said grooves in the manner shown most clearly in Figure 6. From Figure 4, it will be seen that the grooves 32 have a relatively high lower lip 37 which prevents liquid from escaping from the grooves as it flows downwardly therein.

Designated at 38 is an electrode which projects into the top groove 32 adjacent the inlet conduit 34. Electrode 38 is connected to one terminal of a suitable source of high potential electricity such as an electrostatic machine or its equivalent. The other terminal of said source is connected to the electrode 33 carried by the opposing plate member.

Designated at 39 and 39' are respective mercury reservoirs of insulating material mounted on supporting brackets 40 and 40' secured to the side walls of housing 11. The reservoirs are connected through respective control valves 41 and 41' and flexible conduits 42 and 42' to the inlet conduits 34 of the electrode plates 31 and 31'. The outlet conduits 35 of said plates are connected by respective conduits 43 and 43' to a mercury still. Designated at 44 and 44' are supply conduits leading from the still and arranged to supply distilled mercury to the respective tanks 39 and 39'.

Designated at 45 is a discharge conveyor belt positioned below the electrode plates 31, 31' and

3

arranged to convey waste material passing downwardly between the plates out of housing 11 to a suitable discharge point.

In operation, gold bearing screened sand is deposited into hopper 13 by conveyor belt 21 and passes through the spout 14, where it is dried by the action of heater coil 15. The dried material falls between the plates 31 and 31' and is subjected to a high electrical potential between the mercury streams flowing in the grooves 32 of the two plates 31 and 31'. The particles of material are attracted to the mercury with sufficient velocity to impart relatively high momentum to the heavier gold particles. The gold particles therefore acquire enough momentum to overcome the surface tension of the mercury and to penetrate therein. The mercury surface becomes covered with particles of dust which are scraped off by the scraper bars 36 as the mercury flows past said bars. The waste material drops down between the plates to the discharge conveyor belt 45 and is carried off thereby. The gold is carried off by the mercury and is recovered at the still. The distilled mercury is returned to tanks 39 and 39' through the supply conduits 44, 44'.

By means of hand wheels 27 and 28, the spacing between the plates 31 and 31' may be adjusted to provide most efficient operation.

Referring now to Figures 7 and 8, the ore hopper is designated at 46, said hopper having a plurality of discharge spouts 47. The spouts are in close proximity to a heating winding 48 which dries the material passing through the spouts. Designated at 49 are spaced vertical electrode plates, each spout 47 being positioned so as to discharge ore material between a pair of adjacent plates. The plates 49 are formed with inclined grooves 32 in each face in the same manner as shown in Figure 2, the grooves being connected by semi-circular elbows 33. Designated at 50 is a mercury inlet conduit which is connected by means of branches 52 to the top grooves of alternate plates 49. Designated at 50' is a second mercury inlet conduit similarly connected to the top grooves of the remaining plates 49. The respective conduits 50 and 50' have projecting therein electrodes 53 connected respectively to the opposite terminals of a source of high potential electricity. Mercury is supplied to the respective conduits 50 and 50' from tanks 51 and 51'. The gold-bearing mercury leaves the plates through discharge conduits 54, 54' connected to the bottom grooves of alternate plates and is delivered to the still where the gold is separated from the mercury by distillation, as in the previously described embodiment of the invention.

The arrangement of Figures 7 and 8 enables a very substantial volume of ore material to be processed in a given period of time. Waste material is carried off in the same manner as described in connection with the embodiment of Figure 1.

While certain specific embodiments of a system for recovering fine gold from gold bearing sands by electrical precipitation have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An apparatus for separating precious metal particles from comminuted ore comprising a hopper having a bottom opening, a pair of parallel

vertical plate members separated by a small gap and positioned so that said gap is substantially below said bottom opening, said plate members being formed with inclined grooves in their opposing faces, conductive liquid streams continuously movable through said grooves, and means establishing a high electrical potential between the conductive liquid streams in the respective plate members.

2. An apparatus for separating precious metal particles from comminuted ore comprising a hopper, outlet means at the bottom of said hopper, a plurality of parallel vertical plate members positioned so that the gaps between adjacent faces thereof are below said outlet means and so that material from the hopper may descend through said gaps, the adjacent faces of the plate members being formed with inclined grooves, conductive liquid streams continuously moving through said grooves, and means establishing a high electrical potential between conductive liquid streams in adjacent plate faces whereby metal particles in the ore material will be accelerated toward the liquid as the ore material descends through the gaps.

3. An apparatus for separating precious metal particles from comminuted ore material comprising a hopper having a bottom discharge opening, heating means at said discharge opening, a pair of parallel vertical plate members separated by a small gap and positioned so that said gap is substantially below said discharge opening, said plate members being formed with inclined grooves in their opposing faces, means connecting the grooves in each face so as to define a continuous channel from the top of each plate to the bottom thereof, a respective stream of conductive liquid in the grooves of each plate member, and means establishing a high electrical potential between the conductive liquid streams in the grooves in the opposing plate faces.

4. An apparatus for separating precious metal particles from comminuted ore material comprising a hopper having a bottom discharge opening, heating means at said discharge opening, a pair of parallel vertical plate members separated by a small gap and positioned so that said gap is substantially below said discharge opening, said plate members being formed with inclined grooves in their opposing faces, means connecting the grooves in each face so as to define a continuous channel from the top of each plate to the bottom thereof, a scraper bar secured to each face and traversing the grooves thereof, a respective stream of conductive liquid in the grooves of each plate member, and means establishing a high electrical potential between the streams of conductive liquid in the grooves in the opposing plate faces.

RICHARD L. GUZZETTI.
